(57) **CLAIM**

The ornamental design for the glove, as shown and described.

DESCRIPTION

FIG. 1 is a perspective view of the glove showing my new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof; and,

FIG. 7 is a bottom plan view thereof.

The bottom of the glove illustrated by a "dash dot dash" broken line represents the bounds of the claimed design and forms no part to the claimed design. The uniform broken lines represent unclaimed environmental subject matter and form no part to the claimed design.
